(57)

CLAIM

The ornamental design for a garden cart as shown and described.

DESCRIPTION

FIG. 1 is a top perspective view of a garden cart showing my design;

FIG. 2 is a bottom perspective view thereof;

FIG. 3 is a top view thereof;

FIG. 4 is a right side view thereof;

FIG. 5 is a left side view thereof;

FIG. 6 is a bottom view thereof;

FIG. 7 is rear view thereof; and,

FIG. 8 is a front view thereof.

The broken lines are for the purpose of illustrating portions of the garden cart which form no part of the claimed design.
